UNITED STATES PATENT OFFICE.

GEORGE WILLIAM HUTCHINSON, OF WALTON, AUCKLAND, NEW ZEALAND.

SPARKING-REGULATOR FOR INTERNAL-COMBUSTION ENGINES.

1,039,407.

Specification of Letters Patent. Patented Sept. 24, 1912.

Application filed April 9, 1912. Serial No. 689,672.

To all whom it may concern:

Be it known that I, GEORGE WILLIAM HUTCHINSON, a citizen of the Dominion of New Zealand, and residing at Walton, Wai-
5 kato, in the Provincial District of Auckland, Dominion of New Zealand, have invented certain new and useful Improve-
ments in Sparking-Regulators for Internal-
Combustion Engines, of which the follow-
10 ing is a specification.

The invention relates to sparking apparatus by which the charge is fired in internal combustion engines.

My object is to automatically regulate the 15 timing of the sparking, so that it occurs at the most advantageous moment, at all speeds of the motor, the sparking being advanced as the speed of the motor increases and retarded as the speed decreases.

20 Figure 1, is a side elevation. Fig. 2, a longitudinal sectional elevation. Fig. 3, a cross section on line A—A, of Fig. 1. Fig. 4, a plan showing a detail.

A governor constructed according to my 25 invention has a frame 1 and a base plate 2 whereby it is affixed to any convenient part of the engine. A cylinder or tube 3 is secured in the frame 1 and prevented from revolving by a set screw 4. A boss or sleeve 30 5 mounted revolvably on the tube 3 is retained in position between the frame 1 and the sleeve 6 fixed on the end of the cylinder 3. Governor balls 7 are mounted upon steel straps 8 attached at one end to the boss 35 or sleeve 5 and at the other end are attached to a boss 10 by screws 11. The boss 10 is mounted revolvably upon the sleeve 6 and has an internal circumferential groove 12 which engages a pin 13 projecting from a plunger 40 14 which is slidable in the interior of the sleeve 6, a slot 15 being provided in the sleeve 6 to allow movement of the pin 13. The sleeve 6 is secured to the frame 1 by means of a set screw 16. A rod 17 provided 45 with a collar 18 fits within the cylinder 3 and is regulatable by a thumb screw 19 screwed into the end of the cylinder and kept in position by a lock nut 21. A spiral spring 22 located within the sleeve 6 bears

at one end against the collar 18 and at the 50 other end against the plunger 14. The end of the rod 23 is provided with coupling 24 (see Fig. 2) having a hole which engages a pin 25 fixed to a rack 26 which gears with a tooth wheel 27 fixed to the commutator 28 55 which is of ordinary description.

Fig. 1 shows an alternative connection of the rod 23 to the commutator. A pin 29 integral with a bar 30 and a coupling 31 is adapted to engage the slot or hole usually 60 provided in the lug of the commutator. The rod 23 passes through a guide 32 provided in the end of the frame 6. The governor is driven by a toothed or sprocket wheel 33 which is secured to the boss 5 by a feather 65 or screw and receives its motion from tooth gearing a chain, or the like. In operation the governor and sparking mechanism are so set that a spark occurs at the "late fire" position when the engine has been stopped. 70

After the engine has been started and the speed of the governor increases the balls fly out under centrifugal force and in so doing they cause the boss 10 to travel in the direction of the boss 5 and the groove 12 engaging the pin 13 causes the rack 26 to move and rotate the toothed wheel 27 and the commutator 28 thereby advancing the timing of the spark by altering the sparking mechanism and so cause the spark to occur 75 80 at the most advantageous time during all speeds of the engine. As the speed of the engine decreases the straps 8 and the spiral spring 22 overcome this centrifugal force and the balls gradually close toward the 85 sleeve thus gradually leading the sparking gear to the "late fire" position.

An engine fitted with the sparking regulator is much safer to start because the 90 sparking cannot occur too early as with other mechanism and thus cause the explosion in the engine to occur too soon and so kick back. The pressure of the spring 22 upon the plunger 14 is regulated by operating the screw 19.

What I do claim and desire to secure by Letters Patent of the United States is:—

A sparking regulator of the kind de-

scribed, comprising a governor, a sliding rod operated by the governor, a rack upon the sliding rod, a commutator, and a toothed wheel on the commutator engaged by the 5 rack, as set forth.

In testimony whereof I have signed my

name to this specification in the presence of two witnesses.

GEORGE WILLIAM HUTCHINSON.
